(57) **CLAIM**

The ornamental design for a shower wand, as shown and described.

DESCRIPTION

FIG. 1 is a front elevational view of a shower wand showing our new design;

FIG. 2 is a right side view thereof, the opposite side being a mirror image of the side shown; and,

FIG. 3 is a top plan view thereof.

The broken line showing is for illustrative purposes only and forms no part of the claimed design.
